BELL FOR BLAST FURNACES

Albert Mohr, Jr., and John P. Grilli, Chicago, Ill.

Application October 9, 1943, Serial No. 505,639

4 Claims. (Cl. 214—36)

In the charging equipment of an iron blast furnace it is necessary to provide two bells to prevent the escape of top gases from the furnace. These bells are controlled so that only one bell is open at a time; that is, when one is open, the other is closed.

The top bell is designated as the small bell, and is usually approximately from four to seven feet in diameter, depending upon the size of the furnace. The bell below the small bell is designated as the large bell, and has a diameter of approximately from thirteen to sixteen feet, depending upon the size of the furnace.

The present invention is more particularly directed to the large bell. With all present large bells the flow and distribution of materials from the large bell into the furnace is subject to many variables. It is of paramount importance in the successful operation of the furnace, that the materials on the large bell flow into the furnace at a uniform rate, and that the bell shall open equally around its entire circumference; otherwise, the amount of materials will not be distributed uniformly, and this will prevent the furnace from attaining its best possible performance.

Such irregular distribution of the materials will cause the furnace to work hot on one side and cold on the other side. At present the large bells are balanced after they are machined, but this balance is upset after the first few hours of operation. The reasons for the unbalancing of the large bell are the depositing of materials on the under side of the bell and the baking on of ore and other materials on the top side of the bell.

These materials do not deposit uniformly and are of different densities, and therefore throw the large bell out of balance, with the result that the large bell will be caused to open first on the side that the bell is heavy, thereby causing a greater amount of materials to be deposited in the furnace on that side.

Another condition which causes the non-uniform distribution of the materials into the furnace is due to the fact that they bake on the top side of the bell, and they will slide off the bell on the cleaner side faster than on the baked section or side, thereby causing the large bell to swing. This condition is of such importance that in many plants the top surface of the large bell is cleaned many times a day, by using bars and snappers to remove the baked-on materials.

In the accompanying drawing diagrammatically illustrative of this invention:

Fig. 1 shows a portion of a hopper and a large bell in position to close the hopper.

Fig. 2 is a sectional view taken on line 2—2, Fig. 1, with parts omitted.

Fig. 3 is a fragmentary view of a portion of the hopper and large bell, showing another form of guiding means.

5 It is the usual practice in furnaces of this character to suspend the large bell 10 from a bell rod 11, which is approximately fifty feet long, and the bell is always centered in the furnace when the latter is cold. However, when the furnace is 10 in generation there is an ever changing temperature distribution within the furnace, and there are times when the center of the large bell 10, and the center of the bell rod 11 at its point of suspension, are not in the same perpendicular axes. 15 This, of course, will cause the bell to swing, with the result that the bell will open on one side in advance of the opening on the other side, and thereby cause unequal distribution of materials 20 in the furnace.

It is one of the objects of the present invention to overcome these difficulties and objections, and to provide improved means for insuring that the large bell will be prevented from so swinging, but 25 will be caused to open uniformly about its entire circumference, thereby insuring a uniform delivery of the materials into the furnace.

In carrying this invention into use, the bell 10 is shown connected to the rod 11, preferably by 30 means of a key 12, and this large bell co-operates with a hopper 13. Supported within this hopper, preferably by the wall thereof, are any suitable number of guide members 14 which may be secured in position in any suitable manner, 35 and are preferably of a wedge-shaped formation. Carried by the bell 10, preferably adjacent the circumferential edge thereof and outside of the bell, are additional guide members 15 which may be of any desired or suitable construction and configuration, and which may be secured in position 40 in any suitable manner. It has been found, however, that the guides 15 may be formed of rods or bars secured to the bell in any manner, such as by screwing one end of the rods into the bell. 45 These guide members 15 are arranged uprightly, one in proximity to each of the guide members 14, and as the bell is opened by lowering the same with respect to the hopper, the guides 15 will co-operate with the guides 14, and thereby maintain the bell against swinging, causing it to open 50 evenly and to the same extent entirely around its circumference.

If desired, a plate or member 16 may be provided to form a closure for the bell itself, and this 55 plate may be supported and secured in position in

any suitable manner, such as by means of rods or bars 17 which are secured to the plate and also to the bell in any suitable manner.

The plate 16 may be partially corrugated, as at 18, or the entire plate may be so constructed, if desired, to compensate expansion thereof under the action of heat, and the contraction thereof. The guides 14 and 15 do not contact when the bell is in a position to close the hopper, but when it is lowered to discharge the material into the furnace, and should the bell start to swing, the guides 15 will strike the guides 14, and the bell will be maintained against any such swinging movement.

The plate 16 forming a closure at the bottom of the hollow bell, will prevent materials depositing upon it, because it will always be hot and above the dew point of the gas leaving the stock of materials, as the influence of the cold charge on the large bell will not keep this plate cold.

The materials on top of the large bell will not bake on the top surface thereof, because the plate or member 16 will prevent the gases in the furnace from passing over the bottom surface of the large bell.

In the form of the invention shown in Figure 3, the guiding means for the bell consists of fins or members 19 secured to the outer face of the bell 10 adjacent the lower edge thereof, which, when the bell attempts to swing while opening, will contact the wall of the hopper and prevent such attempted swinging movement. Any number of these members 19 may be provided, and are suitably spaced around the circumference of the bell.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. A blast furnace bell and hopper, said bell adapted to form a closure for the bottom of the hopper, means for supporting and for moving said bell into open and closed positions with respect to the hopper, spaced wedge-shaped members secured to the inner face of the hopper adjacent the

outlet end thereof, and upright guide bars secured to the bell and projecting thereabove, said guide bars co-operating with the respective wedge-shaped members to maintain the bell against tilting during its opening movement.

2. A blast furnace bell and hopper, said bell adapted to form a closure for the bottom of the hopper, means for supporting and for moving said bell into open and closed positions with respect to the hopper, spaced wedge-shaped members secured to the inner face of the hopper adjacent the outlet end thereof, and upright guide bars secured to the bell and projecting thereabove, said guide bars co-operating with the respective wedge-shaped members to maintain the bell against tilting during its opening movement, there being a space between the guide bars and the respective wedge-shaped members, whereby to maintain the charge in the hopper from wedging between the bars and the guide members.

3. A blast furnace bell and hopper, said bell adapted to form a closure for the bottom of the hopper, means for supporting and for moving said bell into open and closed positions with respect to the hopper, spaced wedge-shaped members secured to the inner face of the hopper adjacent the outlet end thereof, upright guide bars secured to the bell and projecting thereabove, said guide bars co-operating with the respective wedge-shaped members to maintain the bell against tilting during its opening movement, said bell being hollow, and a closure for the open bottom of the bell.

4. A blast furnace bell and hopper, said bell adapted to form a closure for the bottom of the hopper, means for supporting and for moving said bell into open and closed positions with respect to the hopper, spaced wedge-shaped members secured to the inner face of the hopper adjacent the outlet end thereof, upright guide bars secured to the bell and projecting thereabove, said guide bars co-operating with the respective wedge-shaped members to maintain the bell against tilting during its opening movement, said bell being hollow, and a corrugated closure for the open bottom of the bell.
